BY *J. W. Robertson*
ATTORNEY

UNITED STATES PATENT OFFICE.

ELIEL L. SHARPNECK, OF DENVER, COLORADO.

ROTARY DRILLING-ENGINE.

SPECIFICATION forming part of Letters Patent No. 294,514, dated March 4, 1884.

Application filed July 31, 1883. (No model.)

To all whom it may concern:

Be it known that I, ELIEL L. SHARPNECK, a citizen of the United States of America, residing at Denver, in the county of Arapahoe and State of Colorado, have invented certain new and useful Improvements in Rotary Drilling-Engines, of which the following is a specification, reference being had therein to the accompanying drawings.

10 This invention relates to that class of rock-drills which are designed to be run by steam, compressed air, or other motive power, and adapted to be held in the hands of the operator while in operation; and the invention consists in the peculiar construction, combination, and arrangement of parts, hereinafter described and claimed.

15 In the accompanying drawings, Figure 1 shows an elevation of my drill on a small scale. Fig. 2 is a side view on a larger scale, partly in section. Fig. 3 is a cross-section through the line *x x* in Fig. 2, and Fig. 4 is a section of one of the pistons.

20 A is the casing of the engine, constructed as shown, and screwed into or otherwise secured to the head B, which head is provided with a socket, *b*, to receive a rod, C, which is preferably hollow, and carries the handles D E.

25 At F is shown a cylinder, provided with journals G G at top and bottom; and a hardened-steel center, H, which works in a steel step, I, set in the head B. The lower end of the cylinder carries the drill-spindle J, which I prefer to be diamond-pointed and keyed fast to the cylinder, and to work through a hollow ring, K, set in the stuffing-box M. This ring is perforated on one side opposite a pipe, L, screwed into the stuffing-box. Packing V is 30 set in the stuffing-box on each side of the ring K, and is adjusted by the gland N and jam-nut O. The cylinder F has two transverse slots formed in it at right angles to each other, in which work the pistons P, in the usual manner, which pistons are cut away at the central part, so that they will not interfere with each other, and each is divided at the center and recessed to receive a spiral spring, to keep the faces of the opposite parts in contact with the 35 inner surface of the casing A. The casing is provided with an inlet at Q and an outlet, R, and a recessed port at S, for the passage of the steam, compressed air, or other motive power.

It will be observed that the drill is hollow, 55 and has perforations connecting it with the recess in the ring K, and thus water from the pipe L will pass through the perforations into the drill, and as it issues from the bottom thereof will keep the drill cool and wash the 60 pulverized rock out of the hole.

With this construction and arrangement a light, cheap drilling apparatus is produced that can be made to work very rapidly, carried into and worked in any desired position, 65 and one that will be very durable and not liable to get out of order. Being provided with handles arranged as shown, it can be readily held in any desired position, and will be found very convenient in positions where 70 other drills cannot be used, as it can be used with the engine held in narrow crevices, where a man could not stand to operate such drills as have heretofore been devised for this purpose. By means of the long handle projecting from the rear of the engine, the drill can be held in a variety of positions that it could not be held in where the operator has to 75 grasp handles arranged at the side of the engine.

80 I do not limit myself to the exact construction of the engine, as it is evident that any style of cylinder and pistons may be employed with my handles.

85 What I claim as new is—

1. A rotary engine having its revolving and operating cylinder provided with journals at its opposite sides, one of which has a socket for a drill and the other a conical center bearing, substantially as described.

90 2. The combination, with a rotary engine having an elongated journal, forming a bearing for a socket for a drill, of the rod C, provided with the handles D and E, substantially as described.

95 3. The combination, with the casing A, of the head B, provided with a step, I, and socket *b*, the rod C, handles D E, cylinder F, having center H, drill J, and pistons P, all constructed and arranged substantially as shown 100 and described.

In testimony whereof I affix my signature, in presence of two witnesses, this 23d day of July, 1883.

ELIEL L. SHARPNECK.
